P. SPIES.

DRAINING ATTACHMENT FOR THE DASHBOARDS OF MOTOR VEHICLES.
APPLICATION FILED OCT. 21, 1918.

1,297,030.

Patented Mar. 11, 1919.

UNITED STATES PATENT OFFICE.

PETER SPIES, OF CLEVELAND, OHIO.

DRAINING ATTACHMENT FOR THE DASHBOARDS OF MOTOR-VEHICLES.

1,297,030.

Specification of Letters Patent. Patented Mar. 11, 1919.

Application filed October 21, 1918. Serial No. 258,972.

To all whom it may concern:

Be it known that I, PETER SPIES, a citizen of the United States, residing at Cleveland, in the county of Cuyahoga and State of Ohio, have invented a new and useful Draining Attachment for the Dashboards of Motor-Vehicles, of which the following is a specification.

This invention relates to an improved 10 draining attachment for the dash-board of a motor-vehicle comprising a hood which overlaps the top and side edges of and extends forwardly from the dash-board and is employed in serving as a cover for the engine of the vehicle, and this invention pertains more especially to an attachment comprising a trough arranged transversely of the upper portion of the outer side of the dash-board and a water-tight joint formed 15 between the upper end of the inner side portion of the trough and the dash-board, so that any water passing to the inner side of the dash-board, at the joint formed between the top edge of the dash-board and the top 20 of the aforesaid hood, shall be received by said trough and conducted toward the sides of the hood and out of the way of any electric wiring or electrical connections or devices that may be applied, under said trough, 25 to the dash-board.

The primary object of this invention is to keep water, that may find passage to the outer side of the dash-board from between the top edge of the dash-board and the 30 hereinbefore mentioned hood, away from said electrical connections or devices.

Another object is to facilitate the application of my improved draining attachment to the dash-board, to expedite the assemblage of the component parts of said attachment, to have said attachment simple and durable in construction, and to render any member of said attachment readily renewable.

With these objects in view, and to attain any other object hereinafter appearing, this invention consists in certain features of construction, and combinations and relative arrangements of parts, hereinafter described 45 in this specification, pointed out in the claims, and illustrated in the accompanying drawings.

In said drawings, Figure 1 is a vertical section taken centrally through the dash-board and through the rear portion of the

hood which straddles the dash-board and through my improved draining attachment applied to the outer side of the upper portion of the dash-board. Fig. 2 is a vertical section taken along the line 2—2, Fig. 1, 60 looking toward the dash-board. Fig. 3 is a section taken along the line 3—3, Fig. 2, looking downwardly. Fig. 4 is a vertical section taken along the line 4—4, Fig. 3, looking rearwardly. Fig. 5 is a vertical section taken along the line 5—5, Fig. 2, looking outwardly.

Referring to said drawings, A indicates the dash-board of a motor-vehicle, and B indicates the hood overlapping the top and 70 side edges of and extending forwardly from the dash-board. The hood B therefore straddles the dash-board and is applied in any approved manner.

My improved draining attachment for 75 said dash-board preferably comprises a plate C arranged opposite and abutting against the forward or outer side of the upper portion of the dash-board adjacent the top edge and centrally between the side edges of the 80 dash-board. Said plate is secured to the dash-board in any approved manner and adapted to be employed in receiving the screw-threaded rear end of a stay-rod D employed in tying the radiator (not shown) 85 arranged at the forward end of the hood B to the dash-board and screwed into said plate. Said plate has upwardly converging side edges 6, as shown in Fig. 4 and in dotted lines, Fig. 2.

My improved draining attachment also 90 comprises two bars E arranged transversely of the outer side of the upper portion of the dash-board between the plate C and opposite side edges respectively of the dash-board and spaced downwardly from the top edge of the dash-board. Each bar E is somewhat inclined and extends downwardly in the direction of the adjacent side of the hood B. Each bar E (see Fig. 4) has its 100 inner transverse edge 7 inclined and facing downwardly to conform to and abutting against the adjacent side edge of the plate C which has a downwardly facing shoulder C' overlapping the top edge of said bar, and 105 said shoulder, said side edge of said plate and said edge of said bar serve therefore to facilitate the positioning of said bar during the application of the bar to the dash-board. Each bar E has its outer transverse edge 8 110

inclined and facing upwardly and laterally of the hood B, as shown in dotted lines, Fig. 2.

F indicates binding-posts or devices, for electrical connections or appliances, arranged at the outer side of the dash-board and under the bars E and spaced from the sides of the hood and applied to the dash-board in any approved manner. My improved draining attachment is designed to prevent the passage of water to said binding-posts or devices from between the top edge of the dash-board and the hood and essentially comprises a trough G arranged at the outer sides of the bars E, and consequently over said binding-posts or devices, and extending from the outer end of one of said bars to the outer end of the other of said bars. The plate C, the bars E and the trough G are supported from the dash-board, and preferably the upper part 10 of the inner side portion of the trough extends upwardly into proximity to but is spaced downwardly from the top of the hood. Said part of said portion of the trough is arranged opposite and abuts against the outer sides of the bars E, and each end of said part of said portion of the trough has a rearwardly projecting flange 12 overlapping and abutting against the outer transverse edge 8 of the adjacent bar. Said portion of the trough extends above the bars E so as to effect the formation, between each bar E and the outer side of the dash-board, of a recess 13 having its bottom formed by said bar. The recesses 13 and any space formed between but above the upper extremities of the bars E and not occupied by the plate C, are occupied by a body of cement, such, for instance, as putty H which forms a substantially watertight joint between the upper end of the inner side portion of the trough and the dash-board. The body of cement H overlaps the top edge of the inner side portion of the trough and has a rounded top surface sloping toward the trough and arranged to effect the drainage, into the trough, of water passing to the outer side of the dash-board from between the top edge of the dash-board and the hood. Preferably the lower part 15 of said portion of the trough extends downwardly and forwardly from the bars E, and the outer side portion 16 of the trough extends upwardly and forwardly and in front of the upper part 10 of the inner side portion of the trough, and hence the contour of the trough in cross-section and the arrangement of the outer side portion of the trough relative to the inner side portion of the trough are such that there is little liability of the passage of water, which may find access to the top surface of the body of cement H, across instead of into the trough. The body of putty or cement H therefore constitutes means for effecting the drainage, into the trough, of

water passing to the outer side of the dash-board from between the top of the hood and the top edge of the dash-board.

It will be observed that the side edges 6 and shoulders C' of the plate C are arranged as required to oppose any force tending to swing or move the bars E downwardly toward each other, and the trough G by the overlapping, by its flanges 12, of the upwardly facing inclined outer transverse edges 8 of said bars, ties the outer ends of said bars together and opposes any force tending to displace said bars endwise from said plate. It will be observed therefore that the plate C affords material support to the bars E and trough G, but, of course, the trough is preferably also secured to the dash-board by screws I which have their shanks extending through the upper part of the inner side portion of the trough and through the bars E and into the dash-board and have their heads abutting against the forward side of said portion of the trough. Said screws are arranged higher than the outer side portion of the trough for convenience in the manipulation of a screw-driver employed in driving the screws into place. It will also be observed that the upwardly facing inclined outer transverse edges 8 of the bars E form seats, as desired, for the trough which is mounted, at its flanges 12, on said seats preparatory to the application of the screws I.

What I claim is—

1. The combination, with the dash-board of a motor-vehicle, and a hood straddling and extending forwardly from the dash-board, of two bars arranged transversely of the outer side of the dash-board at opposite sides respectively of a point centrally between the side edges of the dash-board, a trough extending longitudinally of said bars and having the upper part of its inner side portion arranged opposite the outer sides of and extending above said bars, said bars and the trough being supported from the dash-board, and the recess formed at the top of each bar between the trough and the dash-board being occupied by cement.

2. The combination, with the dash-board of a motor-vehicle, and a hood straddling and extending forwardly from the dash-board, of two bars arranged transversely of the outer side of the dash-board at opposite sides respectively of a point centrally between the side edges of the dash-board, a trough extending longitudinally of said bars and having the lower part of its inner side portion extending downwardly and forwardly from said bars and having the upper part of said portion arranged opposite the outer sides of said bars and having its outer side portion extending upwardly and forwardly and in front of the said upper part of the inner side portion of the trough, screws extending through said upper part

of the inner side portion of the trough and securing the trough and the bars to the dash-board, and means for effecting the drainage, into the trough, of water passing to the 5 outer side of the dash-board from between the hood and the top edge of the dash-board.

3. The combination, with the dash-board of a motor-vehicle, and a hood straddling 10 and extending forwardly from the dash-board, of two bars arranged transversely of the outer side of the upper portion of the dash-board at opposite sides respectively of a point centrally between the side edges of 15 the dash-board and each sloping somewhat downwardly toward the adjacent side of the hood, and a trough arranged at the outer sides of said bars and extending from the outer end of one of said bars to the outer 20 end of the other of said bars and tying the bars together, the trough and the bars being supported from the dash-board, and there being a substantially water-tight joint formed at the top of each bar between the 25 trough and the dash-board.

4. The combination, with the dash-board of a motor-vehicle, and a hood overlapping the top and side edges of and extending forwardly from the dash-board, of two bars 30 arranged transversely of the outer side of the upper portion of the dash-board at opposite sides respectively of a point centrally between the side edges of the dash-board and each supported from the dash-board 35 and having an upwardly facing inclined outer transverse edge, and a trough arranged at the outer sides and extending longitudinally of said bars, each end of the inner side portion of the trough having a 40 flange overlapping the outer transverse edge of the adjacent bar.

5. The combination, with the dash-board of a motor-vehicle, and a hood straddling and extending forwardly from the dash-board, of a plate arranged opposite the outer side of the dash-board adjacent the top edge and centrally between the side edges of and secured to the dash-board and having upwardly facing inclined side edges; 45 two bars arranged transversely of the outer side of the upper portion of the dash-board 50

between said plate and opposite side edges respectively of the dash-board and each having an upwardly facing inclined outer transverse edge, a trough arranged at the outer 55 sides and extending longitudinally of said bars, and means above said bars for effecting the drainage, into the trough, of water passing to the outer side of the dash-board from between the hood and the top edge of 60 the dash-board, each end of the trough having a flange overlapping the outer transverse edge of the adjacent bar, and the inner transverse edge of each bar being inclined and facing downwardly and abutting 65 against the adjacent upwardly facing inclined side edge of the aforesaid plate.

6. The combination, with the dash-board of a motor-vehicle, and a hood straddling and extending forwardly from the dash-board, of a plate arranged opposite the outer side of the dash-board adjacent the top edge and centrally between the side edges of and secured to the dash-board and having upwardly facing inclined side edges, 70 two bars arranged transversely of the outer side of the upper portion of the dash-board between said plate and opposite side edges respectively of the dash-board, each bar having a downwardly facing inclined inner transverse edge abutting against the adjacent side edge of said plate; a trough arranged at the outer sides and extending longitudinally of said bars, and means above 75 said bars for effecting the drainage, into the 80 trough, of water passing to the outside of the dash-board from between the hood and the top edge of the dash-board, each end of the trough having a flange overlapping the outer transverse edge of the adjacent bar, 85 and the aforesaid plate being provided at the top of the inner end of each bar with a downwardly facing shoulder overlapping the top edge of said bar.

In testimony whereof, I sign the foregoing 95 specification, in the presence of two witnesses.

PETER SPIES.
